UNITED STATES PATENT OFFICE.

CHARLES W. HARRIS, OF SALEM, CONNECTICUT.

AUTOMOBILE-LAMP.

984,088.

Specification of Letters Patent. Patented Feb. 14, 1911.

Application filed November 15, 1909. Serial No. 528,249.

To all whom it may concern:

Be it known that I, CHARLES W. HARRIS, a citizen of the United States, residing at Salem, in the county of New London and State of Connecticut, have invented certain new and useful Improvements in Automobile-Lamps, of which the following is a specification, reference being had to the accompanying drawings.

10. My invention relates to improvements in lamps and particularly to improvements in lamps adapted for use upon road vehicles, such as automobiles; and an object of my invention is to provide a lamp which will 15 be simple in construction, relatively cheap in construction and efficient in use. Another object of my invention is to provide a lamp of the class described which may readily be repaired and the cost of upkeep 20 of which will prove small.

In the drawings illustrating my invention and the best mode now known to me of applying that principle, Figure 1 is a side elevation of my new lamp; Fig. 2 is a plan, 25 part of the cover being shown broken away to show the interior; Fig. 3 is a section on the line A—A of Fig. 2; and Fig. 4 is a detail of the number-plate.

In the top *a* and the bottom *b* there are 30 formed parallel with and at a short distance from the front edge of each a shallow groove *c* and parallel with and at a short distance from the lateral edges of each, shallow grooves *d*, *d'*. In the grooves *c* there is 35 fitted a piece of glass *e* which may be uncolored; in the grooves *d* there is fitted a pane of glass *f*, which may be colored, as red; and in the grooves *d'* there is fitted a third pane of glass *g* which may be colored, 40 as blue. A number-plate *h* is formed of a single sheet of metal or other suitable material in which are formed, as by stamping out, the figures and letter indicating the registration or license number of the 45 vehicle. In the edge portions of this number-plate *h* are cut V-shaped notches *i* and are 50 formed the holes *j*. The lateral sections *h*, *h'* of the plate *h* are bent at right angles to the middle section *m* and the edge portions are bent at right-angles to the main 55 body-portion of the plate to form flanges. The number-plate *h* thus bent is placed between the cover or top *a* and the bottom *b* of the casing of the lamp and is fastened in

place by the screws *n* which pass through 55 the top or cover and the bottom into the holes *j*. The back *o* of the casing of the lamp is formed with grooves *d''* in which engage the rear edges of the lateral or side panes of colored glass *f*, *g* and which is 60 formed with a centrally-disposed hole *p* through which projects the base-plug end of a glow lamp *q*. The cover *a* and the bottom *b* are each formed on its inner face with a recess *r* shaped to receive a part of the bulb 65 of the glow lamp *q* and the latter is thus held in place firmly. Screwed upon the base-plug end of the glowlamp *q* is a socket *s* which carries the electric wires *t* which conduct the current to and from the glow 70 lamp. The connection between the lamp-socket *s* and the base-plug of the lamp *q* is shielded from the elements (snow, rain, etc.) by the walls *u* and lid *v* of a box-like compartment *w* provided at the back of the 75 casing. The lid *v* carries the lamp-socket *s* which is mounted in a central hole *v'* free to be turned, so as to screw upon the base- 80 plug of the lamp.

The number-plate, being mounted at a 80 distance from the panes of glass, is brought out into bold relief, when the glow-lamp *q* is lit; and this number plate further serves as a screen to guard the panes of glass from 85 breakage. Should the panes of glass become broken, they are readily replaced by simply removing the cover. Where uncolored glass is used, the number opposed to it will preferably be painted or otherwise colored black; while opposite the colored glass panes the sections of the number-plate will be preferably painted white. The end portions *w* of the number-plate *h* are fastened, as by the screws *n'* to the back *o*, thereby producing a rigid structure but 90 one which may, nevertheless, be readily dismantled for repair, inspection or adjustment.

I claim:

A lamp consisting of a casing having top 100 and bottom casing members and transparent sides fitted therein; an apertured plate fitted between said top and bottom casing members and fastened thereto, thereby fastening the latter together, said plate lying 105 substantially parallel with said sides; an illuminating device interposed between said casing members; a box-like extension which

is formed on one side of said casing and provided with a lid and in which the base end of said illuminating device is mounted; and a socket device which is rotatably mounted in said lid and is arranged to engage said base end.

Signed at said Salem this 29th day of

October, A. D. 1909, in the presence of the two undersigned witnesses.

CHARLES W. HARRIS.
